James Blows

Letters Patent.

The Schedule referred to in these Letters Patent and making part of the same, containing a description in the words of the said James Blows himself, of his improvement in overcoming friction on all kinds of machinery by the application of compound friction rollers.

To all to whom these presents shall come.

Be it known, that I, James Blows, of Norfolk Borough in the County of Norfolk, and State of Virginia, have invented a new and useful improvement in the art of overcoming, or lessening of friction on all kinds of machinery by the application of compound friction rollers and that the following is a full and exact description of the construction and operation of the machine aforesaid invented or improved by me, to show the advantages resulting from the application of friction rollers to all kinds of machinery.

First I have eight or more frames made of brass, copper, cast or bar iron, or any other material sufficiently strong to sustain the weight required, according to the size of the machine, and so constructed as to contain seventeen large friction rollers between four of those frames. By screw bolts. There is to be attached (on a large scale) severable metal boxes, to each frame, in which the large arms of seventeen of the friction rollers play, surrounded by small friction roller in each box, of any size, or metal, according to fancy. My model is built on a small scale, of half an inch to the foot, except the guides, which are $\frac{1}{8}$ of an inch to the foot, and exhibit my full plan and manner of placing my large compound friction rollers, without the severable boxes, and the small friction rollers in them, on which the guides of the large friction rollers play, which I also claim as my invention. The large wheel supports the large wheel of a first mill, or steam boat of sixteen feet

feet diameter, with its quidgous or axles kept on the periphery of the two large friction rollers, by two small side friction rollers of one inch diameter. Each of those $\frac{3}{4}$ rollers are on a scale of one inch to the foot. Then the axle of this large, two inch double friction roller is kept in its station with the centre of its axle revolving on the periphery of one large friction roller of $3\frac{1}{2}$ inches diameter, and is kept in its station by four side friction rollers; then this large $3\frac{1}{2}$ inch friction roller is likewise kept in its station by four other side friction rollers, the quidgous of which roll over on the periphery of two other large $\frac{3}{4}$ rollers of one inch and $\frac{1}{4}$ diameter, the quidgous of these inch and quarter $\frac{3}{4}$ rollers play in the bray boxes as you see in this model, as do all the side friction rollers, which I claim as my invention, but on a large scale, they will all play in the boxes surrounded by the small friction rollers as above stated. The axle trees of a carriage, car, or quidgous of a mill, may be turned off, much smaller than usual, not allowing anything forward; then to prevent their heads wear altogether, a Bray composition or metal box is placed permanent onto them, which makes them but little, if any, larger than is common, when calculating them to wear a long time. These four of these frames are to be attached together at proper distances, with screw bolts and thimbles or washers, with all their friction rollers as above stated, and are to be placed under each quidgous of a steam boat or quiet mill, or on the top of each axle tree of a car, or carriage, where the friction is intended to be lessened or overcome. What I claim as my invention or improvement, is, the mode of preventing the axles or quidgous from wear by applying composition or metal boxes of any kind, stationary or otherwise, around them, and the method of applying the large friction rollers with the frames and movable boxes, & with or without the small friction rollers under the quidgous of the large friction rollers, which are not immediately

immediately under the heels of ears or guides are, as usual, otherwise applied, preventing both friction and wear on the sole of friction rollers that move remarkably slow to what the axletrees or main guides do.

Mitigated
